OTHER PUBLICATIONS

Insul-Caps that Keep Medicine Bottles Clean and Helps the Loading of Medicine, insul-Cap, amazon.com, [Post date: May 3, 2023],

FIG. 1 is a right-side perspective view of a container adapter for a removably attachable syringe;

FIG. 2 is a left-side perspective view thereof;

FIG. 3 is a front view of the container adapter of FIG. 1, showing how it may be placed upon a container, with the back view being a mirror image thereof;

FIG. 4 is a cross-sectional view of the container adapter of FIG. 1, along an imaginary line depicted using dashes in FIG. 2;

FIG. 5 is a close-up view of a portion of the cross-sectional view of FIG. 4;

FIG. 6 is a right-side view of the container adapter of FIG. 1;

FIG. 7 is a left-side view thereof;

FIG. 8 is a top view of the container adapter of FIG. 1;

FIG. 9 is a bottom view thereof;

FIG. 10 illustrates an exploded view showing individual components of the assembly depicted in FIG. 1;

FIG. 11 illustrates an as-assembled perspective view of the container with container adapter fitted thereupon from FIG. 1, now illustrating how a syringe may be attached thereto;

FIG. 12 is a side view of the assembly illustrated in FIG. 11, with the back view being a mirror image thereof;

FIG. 13 is a cross-sectional view of the assembly illustrated in FIG. 11, along an imaginary line depicted using dashes in FIG. 12; and,

(Continued)

FIG. 14 is a close-up view of a portion of the cross-sectional view of FIG. 13.
